UNITED STATES PATENT OFFICE.

WINFIELD HANCOCK YOST, OF MONTREAL, QUEBEC, CANADA, ASSIGNEE TO NATIONAL
DUMP CAR COMPANY, OF CHICAGO, ILLINOIS, A CORPORATION OF MAINE.

DUMP-CAR.

1,072,684.

Specification of Letters Patent. Patented Sept. 9, 1913.

Application filed November 16, 1911. Serial No. 660,703.

To all whom it may concern:

Be it known that I, WINFIELD HANCOCK Yost, of the city of Montreal, in the Province of Quebec, Canada, a citizen of the 5 United States, have invented certain new and useful Improvements in Dump-Cars; and I do hereby declare that the following is a full, clear, and exact description of the same.

10 This invention relates more particularly to dump cars having movable gravity dumping members adapted to be controlled by operating mechanism operable from the end of the car, the invention being especially designed for application to a car of the type having longitudinally extending shafts located beneath and adapted to operate gravity dump doors and whose ends, to which the operating mechanism is applied, are located adjacent the ends of the car.

15 The invention has for an object to provide in connection with an easily accessible dump member operating mechanism, means 25 for protecting such mechanism from injury due to shocks, as when the corners of the cars are bumped, or from push poles.

20 For further comprehension of the invention, and of the objects and advantages 30 thereof, reference will be had to the following description and appended claims, and to the accompanying drawings forming part of this specification in which similar reference characters indicate the same parts 35 and wherein—

Figure 1 is an end elevation of a car having the invention applied thereto. Fig. 2 is a horizontal view of the end portion of the car, one half the view being in plan and the other half in section on the line 2 2 40 Fig. 1. Fig. 3 is a detail transverse vertical section taken on the line 3 3 Fig. 2. Fig. 4 is a detail perspective view of the operating gear protecting device. Fig. 5 is a detail cross section of the floating stirrup link, illustrating particularly the manner of mounting the locking pawl reversibly thereon, the view being taken on line 5 5 Fig. 1; Fig. 6 is a detail horizontal section on the line 6 6 Fig. 1; and Fig. 7 is a detail perspective view illustrating particularly the operating gear.

In the drawings I have shown one end

only of a dump car as such showing is considered sufficient to properly illustrate the 55 invention, it being obvious that the construction herein illustrated can be duplicated on the other end of the car when desirable.

Referring now to the drawings the end 60 wall of a dump car hopper is shown at 1 and a portion of the side walls at 2, a part 65 of the understructure comprising a center sill 3, side sills 4 and end sill 5 being also shown. A pair of dump doors are indicated at 6, one at each side of the center sill, such doors being hinged at their inner or adjacent edges in any suitable manner to swing inwardly and downwardly when opening, the end portions of a pair of laterally movable shafts which are the type here 70 shown to operate the doors being shown at 7, while the inclined shaft supporting rails in the end sill are indicated at 8. These shafts act upon the doors in a well known 75 manner while the detail construction of the above mentioned parts may be of usual or approved type and forms no part of my invention and is therefore not considered necessary to describe in detail as the invention 80 relates chiefly to the protecting of such mechanism from injury and strengthening the car corners, some of the details of the mechanism for rotating the shafts to cause them to reciprocate laterally presenting also 85 novel features. The operating means here shown by which these shafts 7 are reciprocated laterally along the rails 8 comprises a lever 15 freely mounted at one end thereon and carrying a pawl 16 adapted to engage a ratchet wheel 17 fixed on the shaft to rotate the latter, a chain 18 winding on the shaft as the latter is rotated and causing it to thereby travel along the rail in a well known manner. The shaft is locked 90 against reverse movement by means of a floating stirrup link comprising a one piece member 20 having one end bent to U-shape as shown and freely mounted on the shaft and having its opposite end pivotally connected as at 21 to one end of a link bar 22 whose other end is pivoted to a bracket 23 riveted on the end sill 5, the link 20 carrying a locking pawl 24 adapted to engage a second ratchet wheel 25 also rigid 100 105 on the shaft 7, the U-shaped end of the

link forming a stirrup inclosing the lever and ratchet wheels. This U-shape construction of the end of the link protects the ratchet wheels and lever end and holds all these parts in proper position and obviates any chance of the pawls and ratchets moving out of engagement with each other.

As seen in Fig. 6 the end of the bracket 23 to which the link bar 22 is attached is offset from the part fixed to the end sill in order to cause the link bar to bear thereagainst when the doors are closed to prevent any chance of the links passing dead center position.

15 The locking pawl may be mounted in the link by means of a bracket 26 having one end bent to U-shape to form a stirrup 26' in which the head of the pawl is placed, the opposite end of the bracket 26 being perforated and secured to the link by a bolt or rivet 27 passing through the perforated end of the bracket and one of a pair of openings 28 in the link and which are spaced equally on opposite sides of the median line thereof, 25 the pawl being pivoted on a bolt or rivet 29 passing through the perforated legs of the stirrup and the other one of the said openings in the link.

It will be noted that the bracket 26 may 30 be readily reversed in position as indicated in Fig. 1 according to the side of the car on which the link is to be placed, thus rendering right and left construction for the links on opposite sides of the car unnecessary.

35 The operating gear just described is located outside of the end sill (the end of the shaft projecting through the usual slot 5^b therein) in order to make it easily accessible and to facilitate operation thereof. Heretofore however, the advantage derived from so 40 locating the operating gear has been to a considerable extent offset by its liability to injury from corner shocks or from other causes because of its exposed position. To 45 obviate this difficulty and at the same time secure the advantage of the easily accessible operating gear I have extended the corner of the car longitudinally beyond the end sill in a manner to protect the operating gear and also to strengthen the corner of the 50 car against shocks. This corner extension preferably comprises a plate 30 bent into channel form with a short flange or leg 30' and a longer flange or leg 30^a and placed 55 vertically in position projecting longitudinally of the car from the end sill with the flanges turned inwardly toward the center of the car, the shorter flange being placed against and riveted to the outer face of the 60 end sill at the corner of the car, the body of the plate being preferably flush with the outer end of the sill. The lower edge of this channel plate, and particularly of the flange 30^a, is braced by a bottom connecting 65 and bracing plate 32 of rectangular shape

having one side turned up to form a flange 33 to which is riveted as at 34 the lower edge of the flange 30^a of the plate 30, the said lower edge of the flange 30^a being preferably on a level with and inclined similarly to the bottom edge of the end sill 5. The opposite side of the bottom plate 32 extends under and is riveted to the bottom angle bar 5^a of the end sill 5. The plate 32 is thus inclined similarly to the inclination of the bottom of the end sill, this inclination of the plate preventing any material such as snow, ice, or material spilled over the end of the car, from lodging on the plate and clogging the operating gear. Of the two remaining 80 sides of the plate 32 the inner side (or that near the center line of the car) is bent to form a downwardly projecting stiffening flange 35 while the opposite side is turned upwardly to form a flange 36 which overlaps and is riveted to the bottom of the corner gusset plate 37 of the car.

The upper edge of the channel plate is braced by a longitudinally disposed angle bar having a comparatively narrow vertical flange 40 riveted as at 41 to the inner face of the corner gusset plate 37, and a wider inwardly projecting horizontal flange 42 riveted at its outer end as at 43 to the horizontal flange 44 of a transversely extending angle bar whose vertical flange 45 overlaps and is riveted as at 46 to the top edge of the flange 30^a, the flange 42 extending longitudinally across the top of the space between the flanges 30' and 30^a and being riveted to the top of the end sill 5. As will be seen from the drawings the width of the flange 42 is less than that of the flange 30^a to allow of operative movement of the lever when the shaft is adjacent the outer end of the rail 8 and the operating gear is inclosed by the protecting structure, the bottom plate 32 preferably being of a transverse width equal to that of the flange 30^a in order to properly brace the latter.

It will be noted that in addition to forming a protecting cover for the operating gear the above described structure also strengthens the corner of the car against shocks.

I claim—

1. A dump car having dump member operating mechanism located outside the body of the car, and an inclosing structure for such mechanism secured to the body of the 120 car and having an opening to permit of lateral movement of the dump member operating mechanism, such opening being accessible from the exterior of the car.

2. In a dump car, an end sill, laterally 125 movable dump member operating mechanism located at the outer side of such end sill, and a protecting structure secured to the car and extending longitudinally thereof and adapted to inclose the said operating 130

mechanism such structure having one side open to permit of lateral movement of the said operating mechanism.

3. A dump car having an end sill comprising an integral member extending from a point adjacent the center of the car transversely to the car side, laterally movable operating mechanism located at the outer side of such end sill, and an inclosing structure 10 separate from and braced by such end sill and projecting longitudinally therebeyond to inclose the said operating gear.

4. In a dump car, the combination with the end sill thereof, of a vertically disposed channel plate with inwardly projecting flanges having one flange secured to the end sill, such plate extending longitudinally of the car beyond the end sill, and top and bottom bracing members extending between the other flange of the channel plate and the end sill.

5. In a dump car, the combination with the end sill thereof, of a vertically disposed channel plate with inwardly projecting flanges having one flange secured to the end sill, such plate extending longitudinally of the car beyond the end sill, and top and bottom bracing members extending between the other flange of the channel plate and the end sill, the lower bracing member being inclined, the top bracing member being of lesser transverse width than the second mentioned flange to cause the latter to project inwardly therebeyond, the bottom member being of a transverse width substantially the same as that of the said second mentioned flange.

6. In a dump car, an end sill, dump member operating mechanism located at the outer side of such end sill, and a box like structure secured to the corner of the car and extending longitudinally thereof and adapted to inclose the said operating mechanism, such structure having its transverse inner side and the adjacent portion of the top thereof open.

7. In a dump car, an end sill, dump member operating mechanism located at the outer side of such end sill and including a lever, and a box like structure secured to the corner of the car and extending longitudinally thereof and adapted to inclose the said operating mechanism, such structure having its transverse inner side and the adjacent portion of the top thereof open to permit of the movement of the lever.

8. In a dump car, an end sill, dump member operating mechanism located at the outer side of such end sill, and a box like structure secured to the car and extending longitudinally thereof and adapted to inclose the said operating mechanism, such structure having one side open and the bottom thereof inclined.

9. In a dump car, the combination with

a bodily movable shaft, and operating mechanism applied thereto, of locking mechanism including a floating plate having one end bent to U-form to inclose the said operating mechanism.

70

10. In a dump car, the combination with a bodily movable shaft, and operating and locking mechanism on said shaft, of a one piece stirrup mounted on such shaft to prevent longitudinal displacement of the said operating mechanism.

75

11. In a dump car, in combination, a laterally movable dump door operating shaft, a lever for operating such shaft, to move it in one direction, of means for locking the shaft against reverse movement, including a ratchet wheel rigid upon the shaft, a link pivotally mounted at one end upon such shaft, a locking pawl carried by the said link and adapted to engage the said ratchet, 80 a second link pivotally secured at respective ends to the other end of the first mentioned link and to the car, such links normally disposed angularly toward one another, and means preventing such links dead centering.

85

12. In a dump car, in combination a laterally movable dump door operating shaft, a ratchet wheel fixed upon such shaft, an operating lever, a pawl carried by the lever 95 and adapted to engage the said ratchet, a second ratchet wheel rigid upon the shaft adjacent the said lever, a link pivotally mounted upon the shaft, a locking pawl carried thereby and adapted to engage the second mentioned ratchet wheel, the said link having the end thereof mounted upon the shaft bent to U-form to form a stirrup inclosing the said lever and ratchet wheels, and means connecting the said link to the 100 car to permit of movement thereof with the said shaft.

105

13. The combination with the door operating shaft, and the ratchet wheel fixed thereon, of a member pivoted thereto, a 110 pawl adapted to engage the said ratchet wheel, a bracket coacting with the said member in carrying the said pawl, and means providing a reversible connection between the said bracket and member whereby the position of the pawl with respect to the member may be reversed.

115

14. The combination with the door operating shaft and the ratchet wheel fixed thereon, of the link 20 pivoted on such shaft 120 and having the perforations equally spaced on opposite sides of its median line, the reversible bracket 26 having one end 26' bent to stirrup form, the bolts 27 passing through the other end of the bracket and one of the said perforations in the link to secure the bracket to the link, the pawl 24 adapted to engage the said ratchet wheel, and the bolt 29 upon which the pawl is 125 pivoted, such bolt passing through the legs 130

65

4
1,072,684

of the said stirrup and the other perforation in the link.

15. In a dump car, laterally movable dump member operating mechanism located outside the end sill thereof, and a covering device adapted to inclose and protect such operating mechanism.

In testimony whereof, I have signed my name to this specification, in the presence of two subscribing witnesses.

WINFIELD HANCOCK YOST.
